TELEPHONE SYSTEM

Max Langer, Berlin-Hermsdorf, and Ernst Horn, Berlin-Friedenau, Germany, assignors to Fides Gesellschaft für die Verwaltung und Verwertung von gewerblichen Schutzrechten mit beschränkter Haftung, Berlin, Germany, a corporation of Germany

Application May 27, 1939, Serial No. 276,140
In Germany May 30, 1938

7 Claims. (Cl. 179—9)

The present invention is concerned with a circuit arrangement for determining fees in automatic remote signalling installations, in particular automatic telephone installations of the type in which the subscriber's meter is used for determining the amount of the fee by marking and initiating special switching operations. Since the meter is associated individually with a particular subscriber it is suitable, as has already been proposed, for identifying a calling subscriber or for registering his telephone number.

When, as is set forth in the present invention, the subscriber's meter is operated in known manner by current increase on the blocking conductor and, for the purpose of initiating and carrying out special switching operations, a longer operation of meter is necessary, circumstances can occur such that during the current increase on the blocking conductor another selector can test on the arrangement to be guarded and thus the danger of double connections arises.

The present invention relates to the avoidance of this occurrence when an operation of the meter is necessary by limiting the current increase on the blocking conductor to a time which is sufficient effectively to operate the meter.

The drawings, comprising Figs. 1 and 2, together form a circuit diagram showing the invention applied to a line identifying arrangement. For the sake of simplicity and clarity, all arrangements and switches which are not completely necessary for elucidating the idea of the invention are omitted.

The two figures should be placed side by side with Fig. 1 to the left of Fig. 2. Across the top of said figures is illustrated the part of a connecting path which extends from a subscriber T_n over the preselector VW , the first group selector $1GW$, and a repeater UE from which a two-conductor junction line a/b extends for example to a distant exchange. As is indicated by the dotted lines outgoing from the first group selector $1GW$, the connection may pass through any number of additional selector switches before reaching repeater UE . The repeater transfers the impulse train sent out from the subscriber's station on the initiation of the connection over the rest of the junction line and is the intermediary for the operations by which the determination of the number of the calling subscriber is initiated. Further, it transmits impulse trains corresponding to the call number over junction line to the station which is associated with a registering arrangement (printing or punching device) for

recording the call number. In addition to the call number other records can be made by the registering arrangement (called number, duration of connection, amount of fee, period, date, etc.).

Below the connecting path, and separated from it in the diagram by a horizontal dot-and-dash line, is a contact field and control relay arrangement KR and an impulse sender SS ; the two are separated from one another by a vertical dot-and-dash line in Fig. 2, KR lying to the left of this line and SS to the right. The arrangement KR consists of a number of control relays and contacts of the meters associated with the individual subscribers. The meter contacts are fastened together, corresponding to the call number of the individual subscribers, in groups of 100. In Fig. 1 the contact field $1H$ (first hundred) is shown in its entirety, while the contact fields $2H$ (second hundred) and $3H$ (third hundred), are only partially shown.

The impulse sender SS after the marking of the number by means of the control relays transmits the impulse trains corresponding to the individual digits of the call number over the junction line to the printing arrangement.

In connection with the drawings detailed description will be given only for the circuits and operations for determining and transmitting the call number.

When the pre-selector VW is set on a free line relays A and B in the first group selector $1GW$ are energised over the subscriber's loop in known manner. Similarly in the blocking conductor the seizing relay C of the group selector and the cut-off relay T of the pre-selector are energised. The meter Za cannot at present operate. When the first and second group selectors are set, a blocking circuit is completed in which the test relay P of the first group selector and the seizing relay $C1$ in the repeater are energized.

The arrangement shown in Figs. 1 and 2 makes possible the determination and transmission of the call number at any desired instant. It can, for example, be accomplished during the setting up of a connection, after the reply of the called station or after the connection has been terminated. It is assumed here that the reply of the called subscriber is the signal for initiating the determination and transmitting of the call number.

It is a common practice to connect potential to one conductor of the talking circuit when the called subscriber replies in order to operate the calling subscriber's meter. In the present ar-

angement it is contemplated that this practice be followed for low valued calls, and that, for high valued calls, the same potential be connected to the speech path, but for a longer period in order to initiate the determination and transmission of the calling station's number. The switching operations in the latter case may be initiated in a simple manner by time zone metering equipment in the path reached over the repeater UE which, on the reply of the called subscriber, connects a potential corresponding to the metering potential to the lower conductor *b* of the junction line *a/b*. Such time zone equipment is well known, and has been omitted from the drawings since it forms no part of the present invention.

By means of this potential connection the following circuit is completed: earth in repeater UE, contact 68c2, winding of relay ZE, choke Dr3, lower talking conductor *b* and to the battery potential connected to the time zone arrangements. The relay ZE in the repeater UE operates and completes the following circuit: earth, contact 65c2, winding I of relay U, contact 64ze, 55s, 56k, resistance W11, battery, earth. In this circuit relay U operates, closes contact 61u and thus completes the following circuit: earth, winding II of relay U contacts 62ze, 61u, 54s, winding of relay K, battery, earth. In this circuit moreover, apart from the winding II of relay U, the relay K of the impulse sender SS energises, opening its contact 56k and thus the circuit indicated above for winding I of relay U is broken. The completion of the energising circuit of relay U (over winding I) of other repeaters is thus prevented. Further, the relay U closes contact 73u and thus completes the following circuit: earth, contacts 71c1, 73u, winding of relay C2, battery, earth. The relay C2 which at contact 70c2 extends metering current to the subscriber's meter has a delayed armature release and thus operates only after a certain period. Thus the following result is obtained: In Fig. 2 at the top right hand side a repeater UE1 associated with another connecting path is indicated. The contacts 58u and 59u of this repeater correspond to the contacts 60u and 61u of the repeater UE. When the relay U in a neighbouring repeater UE1 operates owing to metering potential on its associated junction line and at this instant before operation of relay K the relay U of repeater UE is energised, then, at contact 60u, the completion of a holding circuit for relay U (winding II) of neighbouring repeater is prevented. The relay U in the neighbouring repeater therefore operates for a short period only. In order that relay U in any repeater when energised momentarily in this manner shall not give rise to faulty operation of the meter by operation of relay C2 in that repeater this latter relay is arranged to have a slow armature operation so that it will operate only after a prolonged energization of relay U.

When the relay C2 is operated on contact 73u being operated for the required length of time it holds for the duration of the connection in the following circuit: earth, contact 71c1, 72c2, winding of relay C2, battery, earth. Relay U remains energised together with relay K until after the determination and transmission of the call number in the following circuit: earth, winding II of relay U, contacts 63c2, 61u, 54s, winding of relay K, battery, earth. Relay K closes its contact 95k and thus connects earth potential to the control relay and the contact field. The relay

5 C2 disconnects winding I of relay U at a further point, namely, contact 65c2. Further, it opens contact 68c2 and closes contact 67c2. Thus earth potential is disconnected from the lower talking conductor. This can be used as a signal bringing switch means in the time zone arrangement into effect and terminating the potential connection to the lower talking conductor. Relays C2 and U energise and the following circuit is completed 10 for the metering relay ZR in the first group selector: earth, battery, resistance W12, contacts 69u, 70c2, choke Dr2, lower talking conductor, windings of the second and first group selectors, choke Dr1 of the first group selector, winding of metering relay ZR, earth.

15 Arrangements are known which make possible the transmission of an impulse over the talking conductors during the conversation without undue disturbances. In the drawings such arrangements are indicated by means of chokes, condensers and equalising networks between the conductors and which are connected to earth.

20 Metering relay ZR in the first group selector operates and closes the contact 2zr thus bringing about a current increase on the blocking conductor so that the meter of the calling subscriber operates. Since the contacts 69u and 70u2 in the repeater remain closed, for the time being 25 the metering relay ZR in the first group selector and hence the subscriber's meter remain energised for some time.

25 The subscribers' meters are so constructed that each metering magnet, in addition to operating the armature which steps the meter wheel, operates an additional contact. The metering contacts are arranged in groups and form a coordinate system of 10 rows of 10 contacts. In the embodiment 100 meter contacts 30 form a contact field: 1H, 2H, 3H. Each contact of a subscriber's meter is arranged in the field according to the call number corresponding to the 100 digit. With the field the contact for the meter of any particular subscriber is situated at the point which corresponds to the number determined by the last two digits of the call number. If the last three digits of a call number are for example, the digits 123, the contact of that particular subscriber's meter is arranged in the contact field 1H for the first 100 and at this field at the point which is formed by the abscissa "2" and the ordinate "3." It is therefore in the field 35 1H at the 3rd contact in the second row.

40 If the last three digits of a call number are 290, the contact of the subscriber's meter is in contact field 2H, second 100's, at the point formed by the abscissa "9" and the ordinate "10." It is therefore the last contact "90" of the 9th row in contact field 2H.

45 In common for all contact fields 1H, 2H, two groups of relays are provided which will be named as "10's control relays Z1—Z0" and "units control relays E1—E10." The 10's control relays are situated on the abscissae running through all contact fields. Thus the control relay Z1 marking the tens digit "1" is on the abscissa "1," and the control relay Z2 marking the tens digit 2 is on the abscissa "2." The units control relays E1—E10 lie on the ordinate multiplied together 50 for all contact fields so that the control relay E1 marking the units digit "1" lies on the ordinate "1," the control relay E2 marking the unit digit lies on the ordinate "2."

55 Each contact field is marked by special switch means. For this purpose in each of the first

two ordinates of contact field $1H$ a winding of $G1$ is provided; in each of the ordinates "3" and "4" a winding of the relay $G2$, in each of the ordinates "5" and "6" a winding of relay $G3$, in each of the ordinates "7" and "8" a winding of relay $G4$ and in each of the ordinates "9" and "10" of the relay $G5$. The contacts (28g1, 27g2, 28g3, 29g4, 30g5) of relays $G1-G5$ connect the relay $H1$ which marks the hundreds digit "1." Resistance $W1$ in parallel with relay $H1$ delays the operation of the relay's armature for a reason which will be explained later.

The same is the case in the other contact fields. In the ordinates of the contact field $2H$ the relays $G6-G10$ are connected, in the field $3H$ the relays $G11-G15$. The contacts (31g6-10) connect the relay $H2$ marking the hundreds digit "2" and the contacts (32g11-15) connect the relay $H3$ marking the hundreds digit "3."

For connecting each of the relays H marking the hundreds digits, 5 relays G are provided for each contact field. Other solutions are possible which mark the contact field in which a particular metering contact lies with a smaller number of switch means.

It is assumed that a subscriber with a number "1125" has set up a connection. The contact of the meter of this subscriber is therefore connected in the contact field $1H$ and at the point which has abscissa "2" and ordinate "5." This therefore is the fifth contact of the second row in the contact field $H1$. When, after the reply of the called party, potential is connected to the lower conductor of the subsequent arranged time zone equipment, the meter Za of this subscriber is energised, and the metering contact "25" in the contact field $1H$ is closed. The following circuit is then completed: earth, contact $95k$, windings I and II of tens control relay $Z2$, metering contact "25" in the contact field $1H$, winding I of relay $G3$, windings I and II of relay $E5$, resistance $W13$, battery, earth. The resistance ratios of the control relays are so selected that in the first place the units relay E operates and then the tens relay Z and final relay G . In the above-mentioned circuit the relay $E5$ first operates and by closing its contact $20e5$ short-circuits its high resistance winding. By means of the current increase thus produced the relay $Z2$ is operated, and closes its contact $7z2$, short-circuiting its high resistance winding I. The further current increase operates relay $G3$ over its winding I.

The relay $E5$ closes its contact $7e5$ in the units contact group EK and thus marks the units digit "5" of the call number in that the common contact $5NK$ of the impulse contact SS is connected over the marking line 5. The relay $Z2$ closes contact $85z2$ in the tens contact group SK and thus marks the tens digit "2" of the call number in that the cam contact $2NK$ of the impulse sender is connected over the marking line 2. The relay $G3$ closes its contact $28g3$ so that the following circuit is completed: earth, battery, winding of relay $H1$, contact $28g3$, resistance $W14$, earth. A resistance $W1$ in parallel with relay $H1$ is connected and causes relay $H1$ to operate with as a slow relay. Relay $H1$ closes contacts $87h1$ in the hundreds contact group HK and thus marks the hundreds digit "1" of the call number in that the cam contact $1NK$ of the impulse sender is connected over the marking line 1. Since it is assumed that the contact fields $1H$, $2H$, $3H$ have the same asso-

ciated thousands group, actually the first thousands group, then by means of the relays $H1-H10$ the thousands digit "1" of the call number is marked. All contacts of the thousands contact group TK therefore are connected to marking line 1 and over this with cam contact $1NK$ of the impulse sender. In the case assumed the connection of this contact is performed by contact $90h1$.

10 All hundreds relays $H1-H10$ have (at their contacts $40h1$, $41h2$, to $42h10$) control over a relay group V/W which effects the connection and operation of the impulse sender SS . The impulse sender is connected by the closing of a metering contact with a considerable delayed operation since one only of the relays E can operate, then one of the relays Z , then one of the relays G and finally one of the relays H (slow). The delayed connection of the impulse sender is necessary so that its operation by normal (short) metering impulses which are transmitted from other connecting paths is prevented. When a metering contact is closed for a short period, and one of the units and tens relays and perhaps one of the relays G can operate, but the normal metering impulse is much too short to operate a hundreds relay H over a G -relay. Hence, it will be seen that a normal (short) metering impulse can never, of itself, start the impulse sender SS .

If simultaneously or almost simultaneously with the connection of potential for a longer period, the normal metering impulse is transmitted over other connecting paths then two meter contacts in the contact field will be closed at the same time. Long before either can operate an H relay, however, the normal metering impulse will have terminated causing the meter contact operated thereby to restore. Finally over the metering contact which is closed for a long time the above-mentioned marking circuits are completed. When this has once been done and the units and tens relays concerned have short-circuited their high resistance windings then no other control relay can be operated notwithstanding the fact that other meter contacts may subsequently be operated by normal metering impulses transmitted over other connecting paths. This is prevented by the locking circuit which extends according to the example as follows: earth, battery, resistance $W13$, winding II of relay $E5$, contact $20e5$, winding I of relay $G3$, metering contact 25 in contact field $1H$, winding II of relay $Z2$, contacts $7z2$, $95k$, earth.

55 The impulse sender SS consists of a switch with forty-eight positions in which the positions $1-12$, $13-24$, $25-36$, and $37-48$, stepped over by the wiper ds are joined to contact segments. The contact segments $1-12$ are connected to contacts $90h1$, $91h2$ to $92h10$ of the thousands contact segments $87h1$, $88h2$ to $89h10$ of a hundreds contact group are connected.

60 The contact segment $25-36$ is connected with contacts $84z1$, $85z2$ to $86z10$ to the tens contact group ZK and the segment $37-48$ with contacts $74e1$, $75e2$ to $83e10$ of the units contact group EK .

65 The impulse sender has ten cam contacts $1NK$ to $10NK$ which are closed in certain positions of the impulse sender.

The contacts of the units tens and hundreds contact group are so connected with the cam contacts of the impulse sender that the contact marking a particular digit in each group is connected over the corresponding marking lines

1—10 with its corresponding cam contact **1NK** to **10NK**. The contacts of the thousands group are however, as has already been mentioned, extended to the marking line 1 and over this to the cam contact **NK1**.

In the given example the following contacts in the individual contact groups are closed **78s5**, **85z2**, **87h1** and **90h1**. After the hundreds relay **H1** is switched in by means of contact **28g3** the following circuit is completed: earth, contacts **40h1**, **43s**, **44w**, **45v**, winding of relay **W**, resistance **Wi5**, battery, earth. Relay **W** operates in this circuit and by opening contact **44w** releases the winding of relay **V** from its short circuit so that this also can operate. The relay **V** closes its contact **46v** and by short-circuiting relay **W** causes it to restore. The following circuit is now completed for relay **X**: earth, battery, resistance **Wi8**, winding of relay **X**, contact **50w**, **49v**, earth. Relay **X** closes contact **48x** and thus connects the magnet **DS** of the impulse sender so that its wiper **ds** is stepped on from the zero position to the first contact. The magnet **DS** has a contact **52ds** which is now closed and relay **Y** is connected: earth, contact **52ds**, winding of relay **Y**, not short-circuited by contact **53x**, resistance **Wi9**, battery, earth. The relay **Y** closes its contact **51y** and short-circuits winding of relay **X**. Contact **48x** opens and disconnects the magnet **DS**. The relay **Y** is restored since contact **52ds** opens and contact **53x** short-circuits the winding. The short circuit for relay **X** is opened at contact **51y** so that this relay operates again. The interaction between relays **X** and **Y** and magnet **DS** continues until the wiper **ds** of the impulse sender has completed a rotation. The cam contacts **1NK** to **10NK** are now closed in a particular manner in dependence on the position of the impulse sender and for a certain period. It is convenient to operate the cam contacts mechanically by means of cams on the shaft. The cam contact **1NK** for example, is closed in positions **2—12**, **14—24**, **26—36** and **38—48** of the impulse sender. The cam contact **2NK** is closed a step later, i. e. in positions **3—12**, **15—24**, **27—36** and **39—48** of the impulse sender, and the cam contact **3NK** in a further position, i. e. in positions **4—12**, **16—24**, **28—36** and **40—43**. In Fig. 2 a table is given which shows the positions in which the different cam contacts are closed.

When the impulse sender has executed its first step the wiper **ds** is operated from zero position to the first contact segment **1—12** and the shaft contact **96ds0** is opened together with the short-circuit for the winding of the impulse relay **J**. As mentioned above the relay **Y** energises after each connection of magnet **DS** at contact **52ds**. When wiper **ds** reaches the first contact the following circuit is completed: earth, battery, resistance **Wi1**, contact **47y**, winding of relay **J**, resistance **Wi6**, earth. In this circuit relay **J** operates which by closing its contact **51j** transmits the first impulse for marking the first digit of the call number of the subscriber on the lower talking conductor on the following path: earth, battery resistance **Wi10**, contacts **57j**, **66u**, **67c2**, winding of relay **ZE**, choke **D13**, lower talking conductor **b**. This impulse travels over the junction line to the station where a registering arrangement is provided (printing or punching device) and typewheels are set corresponding to the impulses transmitted. If the impulse sender has stepped its wiper **ds** into the position **2** the cam contact **1NK** is closed. When relay **Y** is

connected again by contact **52ds** the impulse relay **J** receives no impulse since the following short-circuit is completed for its winding: earth, battery, resistance **Wi1**, contact **47y**, wiper **ds** of contact segment **1—12**, contact **90h1** marking line 1, cam contact **1NK**, resistance **Wi6**, earth. In the given example therefore a single impulse only is transmitted for marking the thousands digit of the call number. In the registering arrangement the type wheel for the thousands digit is therefore positioned on contact "1." The short-circuit of relay **J** completed by the closing of contact **47y** continues as long as the wiper **ds** is on contact segment **1—12** since the cam contact **1NK** is closed in positions **2—12** of the impulse sender.

The impulses for marking the hundreds digit of the call number are transmitted while the wiper **ds** is on the second segment **13—24**. In the hundreds contact group **HK**, the contact **87h1** which is connected with the cam contact **1NK** is closed. In the position **13** of the impulse sender the cam contact **1NK** is opened. It closes in positions **14—24**. After contact **13** has been reached and relay **Y** is connected at contact **52ds**, relay **J** energises since it is not short-circuited and, by closing contact **51j**, transmits an impulse over the lower talking conductor to the registering arrangement. If the wiper **ds** is switched from contact **13** to contact **14** impulse relay **J** can no longer be energised after relay **Y** operates and contact **47y** closes since the following short-circuit exists: earth, battery, resistance **Wi1**, contact **47y**, wiper **ds** of contact segment **13 to 24**, contact **87h1**, marking line 1, cam contact **1NK**, resistance **Wi6**, earth. Thus for marking the hundreds digit of the call number a single impulse only is transmitted. In the registering arrangement the type-wheel for the hundreds digit is thus set on digit "1." The relay **J** cannot be energised on further stepping on of the impulse sender since contact **1NK** remains closed until wiper **ds** has left segment **13—24**. The transmission of the marking signal for the tens digit of the calling subscriber's number follows. In the tens contact group **ZK** contact **85z2** which is connected over marking line 2 with the cam contact **2NK** has been operated. This contact is opened in positions **25** and **26** of the impulse sender and closed in positions **27 to 36**. When the wiper **ds** has reached contact **25** and relay **Y** is connected, relay **J** is energised in the previously mentioned circuit so that an impulse is transmitted to the registering arrangement by the closing of contact **51j**. When the wiper **ds** reaches contact **26** and relay **Y** is operated, relay **J** is again energised and a second impulse is transmitted to the registering arrangement. When the wiper **ds** is stepped further and reaches contact **27**, after relay **Y** is connected and contact **47y** closed, the relay **J** can no longer be energised since the following short-circuit is completed for its winding: earth, battery, resistance **Wi1**, contact **47y**, wiper **ds** of the contact segment **25 to 36**, contact **85z2**, marking line 2, cam contact **2NK**, resistance **Wi6**, earth. When the impulse sender is stepped on over segments **25—36** the relay **J** is no longer operated. For marking the tens digit of the call number two impulses are thus transmitted to the registering arrangement and the type-wheel for the tens digit is set on digit "2."

The units digit of the call number is now marked. In the units contact group **EK** the

contact 78e5 has been operated and is connected with marking line 5 and cam contact 5NK. The cam contact 5NK as can be seen from the table in Fig. 2 is open in positions 37-41 of the impulse sender and closed in positions 42-48.

When the wiper *ds* reaches contact 37, the impulse relay *J* receives an impulse after relay *Y* is connected which is transmitted to contact 51y for registering. When the wiper reaches positions 38, 39, 40 and 41 the relay *J* is energised each time and each time an impulse is transmitted to the registering arrangement. After five impulses have been transmitted to the registering arrangement wiper *ds* reaches position 42 and immediately cam contact 5NK closes. Impulse relay *J* is not energised while the impulse sender is stepped further since the following short-circuit exists for its winding: earth, battery, resistance *W17*, contact 47y, wiper *ds* of the segment 37-48, contact 78e5, marking line 5, cam contact 5NK, resistance *W18*, earth. By means of the five impulses transmitted the typewheel for the units digit in the registering arrangement is set on position "5".

From this last contact wiper *ds* reaches the initial position in which contact 96ds0 is closed and the direct short-circuit for the winding of the relay *J* is again in force. After relay *Y* is connected and releases and relay *X* by short-circuiting its winding at contact 51y, the following circuit is completed: earth, battery, resistance *W17*, contact 47y, wiper *ds* in the zero position, contact 93x, winding II and I of relay *S*, earth. Relay *S* operates in this circuit, opens contact 43s and thus the circuit for relay *V*. Relay *V* opens contact 49v and prevents further operation of the impulse sender *SS*. After relay *Y* releases and contact 47y opens the circuit for relay *S* is broken. Its release is somewhat delayed in view of the short-circuit of its winding II at contact 94s. When relay *S* is energised contact 54s is opened and the circuit for relay *U* (winding II) of the repeater and relay *K* of the impulse sender is broken. Contact 69u opens and disconnects metering potential from the lower talking conductor *b*, restoring the relay *ZR* in the first group selector. Contact 2zr opens and the potential necessary for energising the meter *Za* of the subscriber is again disconnected so that it restores.

Relay *K* releases and opens contact 95k in the impulse sender and the contact for the control relays, so that these restore. When contact 60u closes, other repeaters can be connected with the common impulse sender *SS* for the purpose of determining and registering a call number.

As is clear from the description as long as battery potential is connected over contacts 70c2 and 69u in the repeater to the lower conductor *b* and therefore as long as relay *ZR* in the first group selector and the subscriber's meter *Za* are both energised and determination and transmission of the number of the calling subscriber is continued. Normally the current increase is produced on the blocking conductor by metering relay *ZR* in the group selector for the purpose of operating the meter. When this stronger current is continued for some time, as in the present case, the danger arises that the cut-off relay of another preselector testing on the seized group selector will operate, so that in view of the long application of a stronger current to the *c*-conductor double connections can occur.

To avoid such mistakes entirely the following

arrangement is used: When the relay in the first group selector operates owing to the connection of potential to the lower talking conductor, the contact 2zr is closed. The low resistance *Wi2* is connected over this contact and contact 3ze1 and, in this manner, the current increase necessary for operating the meter is produced on the blocking conductor. Resistance *Wi2* is connected in parallel with a relay *ZE1* whose resistance is higher than that of resistance *Wi2*, and is so arranged that it has a delayed operation and, after opening contact 3ze1 and disconnecting the low resistance *Wi2*, on the one hand maintains the meter *Za* operated for the whole time relay *ZR* is energised, and on the other hand another testing preselector is no longer able to seize the group selector.

A further embodiment is shown which prevents a double seizing of the group selector during the potential connection actually by setting up the blocking conductor in such a manner as that shown in the sketch (under the talking conductor *b* in the group selector *IGW*, Fig. 1) enclosed in a dotted outline.

When the relay *ZR* in the group selector is energised by the potential connection, contacts 4zr and 5zr are closed. The resistance *Wi13* is connected by contact 4zr and an electrolytic condenser *EC* by contact 5zr. The resistance *Wi13* is so arranged that testing on the seized group selector by another preselector is not possible. At the moment when the condenser *EC* is connected a high charging impulse occurs, the meter is operated and is maintained in its operated position over resistance *Wi13* as the relay *ZR* is energised.

The determination and transmission of the call number need not be undertaken for each connection. It can be arranged that these operations only occur in the case of connections of a particular kind, e. g. for high valued connections only.

Naturally, the digit wheels of the meter are also stepped on by the potential connection for the purpose of determining and transmitting the call number. Hence the meter shows an amount which is higher than the fee to be charged. This lack of agreement however can easily be removed since the number of times the registering arrangement is seized is known.

We claim:

1. In a telephone system, a switch, means for seizing said switch, a guard circuit thereupon effective including an electro-magnetic device and a source of potential, said device having a certain potential impressed upon it over said circuit by said source but being normally not operated by said potential, a resistor, a relay, means operated to connect said resistor and the winding of said relay in said circuit to change the potential impressed upon said device by said source thereby to operate the device, said relay operated responsive to the connection of its winding in said circuit and effective thereupon to disconnect said resistor from said circuit, thereby to again change the potential impressed upon said device by said source.

2. In a telephone system, a switch, means for seizing said switch, a guard circuit thereupon effective including a source of current, an electro-magnetic device and a resistor in series, said device being normally traversed by current from said source but not operated by said current, a relay, a second resistor, means operated to con-

nect the winding of said relay in shunt with said first resistor and also to connect said second resistor in shunt with said first resistor thereby to increase the current flow through said device to a value sufficient to operate the device, said relay operated responsive to the connection of its winding in shunt with said first resistor and effective thereupon to disconnect said second resistor to reduce the current flow through said device.

3. In a telephone system, a switch, means for seizing said switch, a guard circuit thereupon effective including an electromagnetic device and a source of current, said device being normally traversed by sufficient current from said source to guard said switch, but said current being insufficient to operate said device, a condenser, means operated to connect said condenser in said circuit in such a way as to supplement the normal current flow through said device by condenser charging current, said device operated by the transitory increase in current flow over said circuit during the charging of the condenser.

4. In a telephone system, a switch, means for seizing said switch, a guard circuit thereupon effective including an electromagnetic device and a source of current, said device being normally traversed by sufficient current from said source to guard said switch, but said current being insufficient to operate said device, a condenser, means operated to connect said condenser in said circuit in such a way as to supplement the normal current flow through said device by condenser charging current, said device operated by the transitory increase in current flow over said circuit during the charging of the condenser and thereafter maintained operated over said circuit independently of said condenser.

5. In a telephone system, a switch, means for seizing said switch, a guard circuit thereupon effective including a source of current, an electromagnetic device and a resistor in series, said device being normally traversed by insufficient current from said source to cause the device to operate, a condenser, a second resistor, means op-

erated to connect said condenser in shunt with said first resistor and also to connect said second resistor in shunt with said first resistor, thereby to increase the current traversing said device to a value sufficient to operate the device, the charging current for said condenser traversing said device to assist in said operation thereof and said device maintained operated, after the charging current has ceased to flow, by current flowing through said two resistors in parallel.

6. In a telephone system, a switch having a blocking conductor normally maintained at one value of potential when the switch is idle and at another value of potential when the switch is engaged, a marginal electromagnetic device connected to said conductor while the switch is engaged but adapted not to be operated by potential of said other value, means operated while the switch is engaged to momentarily vary the potential of said conductor to a value different from said other value and then to restore it substantially to said other value, said device operated by the potential of said different value and thereafter maintained operated by the potential to which said conductor is restored.

7. In a telephone system, a switch having a blocking conductor normally maintained at one value of potential when the switch is idle and at another value of potential when the switch is engaged, a marginal electromagnetic device connected to said conductor while the switch is engaged but adapted not to be operated by potential of said other value, means operated while the switch is engaged to change the potential to a value different from said other value and then substantially at once to change it again to a value intermediate said different value and said other value, said device operated by the potential of said different value and thereafter maintained operated by the potential of said intermediate value.
